UNITED STATES PATENT OFFICE.

FREDRICK W. EISENBERG, OF ANN ARBOR, MICHIGAN.

TAILOR'S GOOSE.

SPECIFICATION forming part of Letters Patent No. 392,595, dated November 13, 1888.

Application filed March 26, 1888. Serial No. 268,463. (No model.)

To all whom it may concern:

Be it known that I, FREDRICK WILLIAM EISENBERG, a citizen of the United States, residing at Ann Arbor, in the county of Washington and State of Michigan, have invented certain new and useful Improvements in a Tailor's Goose, of which the following is a specification, reference being had therein to the accompanying drawings.

10 This invention relates to new and useful improvements in tailors' charcoal-irons, and the invention is intended to form an improvement on the patent granted to me February 21, 1888, numbered 378,297; and the improvement 15 consists in the improved means for locking and unlocking the hinged bottom and the hinged top to and from the body of the iron, all as more fully hereinafter described, and shown in the accompanying drawings, in 20 which—

Figure 1 is a side elevation; Fig. 2, a vertical longitudinal section; Fig. 3, a rear elevation, and Fig. 4 a cross-section on the line *xx* of Fig. 2.

25 A is the body of the iron, provided with a combustion-chamber, B, within which is supported a grate, C, provided with perforations or slots in the usual manner for the admission of air to the fuel, and with a rear guard, D, 30 which extends above the draft-opening E in the rear end of the body to prevent sparks or fuel from falling out through the draft-opening.

F is an ash-pit formed between the bottom 35 and the grate.

G is a bottom hinged at its rear end to the body and tightly fitting against the underside thereof. The forward end of this bottom is provided with an upwardly-extending lug, H, 40 which is provided with a hook, I, into which engagess the lower hooked end of a locking-lever J. The upper end of this locking-lever is pivotally secured in a slot at the forward end of the body and has an upwardly-projecting handle, K, which is within convenient proximity or reach of the hand of the operator holding the handle, and a spring, L, acts against the rear side of the handle K to keep the locking-lever in engagement with the hook 45 I. The lower end of the lever J is provided with a beveled hook, M, to engage with the

hook I, which is similarly rounded or beveled, all so arranged that the operator in extending the thumb of the hand with which he holds the iron may grasp the handle K of the locking-lever J and thereby unlock the hinged bottom, which, dropping by its own weight, permits the ashes to fall out, after which rearrangement of the bottom with the locking-lever J is easily accomplished by bringing the 55 bottom against the body, when the locking-lever will be automatically engaged.

N is a stationary part of the top, through which the draft-opening O is provided for the escaping of the gases of combustion.

65 P is the hinged part of the cover, carrying the handle Q and the sliding spring-latch R, which extends longitudinally through the hinged cover P and terminates at its rear end in a handle, S, which projects beyond the rear 70 end of the body and forms a stop to limit the degree of opening of the hinged top, which, when fully opened, stands at about a right angle to the body, thereby permitting full access to the combustion-chamber to replenish the fuel. 75 The forward end of this locking-latch R projects into a suitable slot or recess, T, in the stationary part of the top, and thereby firmly locks the hinged portion of the top in place. By beveling the forward end of the latch, and 80 also the portion of the stationary top above the recess T, the spring-latch is made to operate automatically in closing the hinged top.

The draft-openings E are provided with draft-doors U, which are hinged at their outer 85 ends at V, so as to operate in an upward direction. This is for the purpose of allowing the knuckle W of the hinged bottom to crowd the doors U out of the way when the hinged bottom is opened, and at the same time permit 90 of forming a tight joint between the rear end of the bottom and the lower edge of the draft-doors to prevent any danger of ashes or sparks falling out.

What I claim as my invention is—

95 1. The combination, in a tailor's charcoal-iron, of the body A, the stationary top N, the hinged top P, carrying the handle Q, and the sliding spring-latch R, provided at its rearward end with a handle, and stop S, independent of 100 said handle Q, substantially as described.

2. The combination of the body A, having

stationary top N, formed with recess T and beveled above said recess, of the hinged top P, recessed longitudinally, as shown, and the spring-actuated catch sliding in the recess in 5 the top and beveled at its forward end and extended at the rear end to form a stop, S, substantially as and for the purpose specified.

3. The combination, with the body A, provided with hinged bottom and draft-openings 10 E, of the draft-doors U, hinged at their outer ends to the end of said body above the knuckle

W of the hinged bottom, and having oppositely-beveled adjacent ends, substantially as and for the purpose specified.

In testimony whereof I affix my signature, in 15 presence of two witnesses, this 19th day of March, 1888.

FREDRICK W. EISENBERG.
